Q. ~~Answer~~ 1

James Dwyer,

By H. B. Wilson Jr.

Attorneys

Patented Oct. 16, 1928.

UNITED STATES PATENT OFFICE.

JAMES DWYER, OF CLEGHORN, IOWA.

HAME TUG.

Application filed March 8, 1928. Serial No. 260,058.

The invention aims to provide a new and improved hame tug embodying novel, easily released and applied means for adjustably connecting a trace with the tug, the construction being such that adjustments may be readily made even in cold weather which so stiffens straps of leather as to make them difficult to manipulate.

In carrying out the invention, I provide a tug of hollow, substantially flat form, into whose rear end the trace is insertable. The upper and lower sides of the tug are longitudinally split at the rear end of the latter, permitting the outer side of the tug to be separated from the inner side thereof, metal plates are provided within the rear end of the tug, and a trace-anchoring screw is insertable through openings in these plates and the outer side of the tug, for securing the trace and tug together, in adjusted relation. It is a further object to provide attaching means for the usual back strap and belly band, embodying rivet portions which secure one of the above-named plates to the tug, at one side of the longitudinal splits of the latter, the other plate being secured to the tug at the opposite side of the splits.

A still further object is to provide a construction in which the main body of the tug may be formed primarily from a single leather strap.

With the foregoing in view, the invention resides in the novel subject matter herein-after described and claimed, description being accomplished by reference to the accompanying drawing.

Fig. 1 is a side elevation showing the tug connected with a trace and portions of a back strap and belly band.

Fig. 2 is a longitudinal sectional view through the tug, the trace and the portions of back strap and belly band being shown in elevation.

Fig. 3 and 4 are transverse sectional views on correspondingly numbered lines of Fig. 2.

Fig. 5 is a sectional perspective view of a portion of the tug.

The form of construction herein disclosed, is preferably followed and while this construction will be described in detail, it is to be understood that within the scope of the invention as claimed, variations may be made.

I make use of a one-piece strap of leather or the like, said strap being folded substan-

tially upon itself as at 6, at its central portion to provide two parallel reaches 7-7^a forming the outer and inner sides of a substantially flat, tubular tug. The longitudinal edges of the strap reaches 7-7^a are turned toward each other to provide upper and lower sides for the tubular tug, said edge portions being shown at 8 and 8^a on the drawing. These inturned edge portions 8-8^a extend from the rear extremity of the tug, to points 9 spaced from the fold 6, and between said points 9 and said fold 6, the strap may well be narrower. Between these narrowed portions of the sides 7-7^a, a reinforcing filler 10 of leather or other desired material is secured by rivets or the like 11 and is adapted for engagement with the usual tug-attaching means 12, of a hame. From the points 9 to points 13 spaced from the rear extremity of the tug, the inturned edges 8-8^a are laced together by appropriate lacing 14 of rawhide or other desired material. Behind the points 13, the inturned edges 8-8^a are free of connection with each other, providing longitudinal splits 15 in the upper and lower sides of the tug, at the rear end of the latter.

Opposed, vertically disposed, metal plates 16-16^a lie against the inner surfaces of the tug sides 7-7^a, at the rear end of the tug. The upper and lower edges of these plates 16-16^a are bent laterally to provide flanges 17-17^a. The flanges 17 lie against the inner surfaces of the flanges 8 and are secured to the latter by rivets or the like 18. The flanges 17^a lie against the inner surfaces of the inturned edge portions 8^a and are secured to the latter by rivet portions 19 of U-shaped attaching devices 20 for a back strap 21 and a belly band 22. The plates 16-16^a and the outer side 7 of the tug, are formed with aligned openings 23 which receive a trace-anchoring screw 24, said screw being threaded into the opening of the plate 16^a.

The trace 25 is receivable in the tubular tug, said trace being provided with longitudinally spaced openings 26, through any of which the screw 24 may be inserted. When this screw is rotated to disengage it from the opening of the plate 16^a, the entire rear portion of the outer tug side 7, may be outwardly swung, and the screw 24 may move outwardly with this side. Then, the trace may be slid within the tug to the desired position and when the outer side of the

tug, that is the rear end of said side, is again swung inwardly, said screw may be readily guided into the proper opening 26 and then threaded into the opening of the plate 16^a. 5 This adjustment may be quickly and easily made even in exceptionally cold weather, having a tendency to so stiffen leather as to make it very difficult to manipulate.

Not only is the construction herein disclosed, rather simple and inexpensive, but it is unusually strong and durable and will well attain the ends for which it is designed. 10 As above stated, the details herein disclosed are preferably followed, but within the 15 scope of the invention as claimed, variations may be made.

I claim:—

1. A hame tug of substantially flat tubular form to receive a trace, said tug having 20 its upper and lower sides longitudinally split at their rear ends to permit separation of the two halves of the tug at the rear end of the latter, two opposed metal plates lying against the inner surfaces of the vertical sides of 25 said tug at the rear end thereof, said plates having lateral flanges at their upper and lower edges lying against the inner surfaces of said upper and lower sides of the tug and extending to the splits of the latter, back 30 strap and belly band attaching means having rivet portions passed through said upper and lower sides of the tug at the inner sides of said splits and through the flanges of the innermost of said plates, means securing the 35 flanges of the outermost of said plates to said upper and lower sides of the tug at the outer sides of said splits, said plates and the outer vertical side of the tug being formed with aligned screw-receiving openings, and a 40 trace-anchoring screw passing through said openings and threaded into the opening of said inner plate.

2. A hame tug comprising a flexible strap folded substantially upon itself at its center

and having its longitudinal edge portions 45 turned toward each other and laced together from points near the ends of the strap to points near the fold of said strap, a reinforcing filler secured between the strap portions from the last named points to the fold 50 thereof for engagement with the usual tug-attaching means of a hame, opposed metal plates secured against the inner surfaces of the end portions of said strap, said plates and the outermost of said end portions of 55 said strap having aligned openings, and a trace-anchoring screw passing through said openings and threaded into the opening of the innermost of said plates.

3. A hame tug comprising a flexible strap 60 folded substantially upon itself at its center and having its longitudinal edge portions turned toward each other and laced together from points near the ends of the strap to points near the fold of said strap, a re-inforcing filler secured between the strap portions from the last named points to the fold 65 thereof for engagement with the usual tug-attaching means of a hame, opposed metal plates lying against the inner surfaces 70 of the end portions of the strap and having lateral flanges contacting with the inner horizontal surfaces of said inturned longitudinal edge portions of said strap, back strap and belly band attaching means having rivet 75 portions passing through one of said in-turned edge portions of the strap and through the flanges of the innermost of said plates, means securing the flanges of the 80 other plate to the other inturned edges of the strap, said plates and the outermost end portion of the strap being formed with aligned openings, and a trace-anchoring screw passing through said openings and threaded into the opening of said inner plate.

In testimony whereof I have hereunto affixed my signature.

JAMES DWYER.
